(74) Attorney, Agent, or Firm — Boyle Fredrickson, S.C.

(57) **CLAIM**

The ornamental design for a rapid recovery grapple hook, substantially as shown and described.

DESCRIPTION

FIG. 1 is a perspective view of a rapid recovery grapple hook showing my new design;

FIG. 2 is a front elevation view thereof;

FIG. 3 is a rear elevation view thereof;

FIG. 4 is a side view thereof;

FIG. 5 is the other side view thereof;

FIG. 6 is a bottom plan view thereof; and,

FIG. 7 is a top plan view thereof.

The broken lines in the figures show portions of the rapid recovery grapple hook, which form no part of the claimed design.
